SEALED CUSHIONING CONTAINER

Harold L. Cohen, Chicago, Ill.

Application November 8, 1950, Serial No. 194,678

5 Claims. (Cl. 206—46)

1

This invention relates to a sealing, cushioning container and has for one object to provide a container which is light, strong and substantially airtight.

Another object is to provide a container with variable internal air pressure.

Another object is to provide a container which will seal the object or objects carried therein from the atmosphere.

Another object is to provide a convenient, practical container in which delicate instruments or other easily damageable objects may be safely packaged and transported by ordinary shipping means.

Another object is to provide a container in which delicate objects may be pneumatically cushioned.

Another object is to provide a hard-shelled container in which delicate objects can be suspended flexibly in relation to and out of contact with the container shell.

Other objects will appear from time to time in the specification and claims.

This invention is illustrated more or less diagrammatically in the accompanying drawings wherein:

Figure 1 is a plan view of the device showing in dotted lines a watch in position for shipment;

Figure 2 is a vertical section taken at line 2—2 of Figure 1;

Figure 3 is an exploded vertical section showing the upper and lower portions of the device separated and with some parts broken away and showing the locking means before the application thereof to said upper and lower portions;

Figure 4 is a section of a modified form;

Figure 5 is a section taken at line 5—5 of Figure 4;

Figure 6 is a sectional view generally similar to Figure 2 and showing a modified form of diaphragm;

Figure 7 is a section illustrating the diaphragm of Figure 6 separated from the housing structure;

Figure 8 is a section illustrating a modified form of diaphragm with a thickened center; and

Figure 9 is a fragmentary section illustrating a modified means for securing two housing or shell members together.

Figure 10 is a section, similar to Figure 2, showing a modified form.

Like parts are indicated by like characters throughout the specification and the drawings.

1 represents a shell which, for convenience herein, will be referred to as an upper shell and 2 represents a second shell similarly referred to herein as a lower shell. Each of the shells 1 and

2

2 is provided with an outwardly extending circumferential lip or flange which is designated generally 3, and which is preferably integral with its respective shell. Across the mouth of each shell is positioned a resilient diaphragm 4 which is secured at its periphery to the inner surface 5 of the flange 3. In practice, the diaphragm may be secured to all or any sufficient portion of this surface or even to the inner circumference 10 of the shells 1 and 2. Experience has indicated, however, that the diaphragm is most effectively secured by being caused to adhere to all, or substantially all, of the inner surface 5 of the flange 3, or by being made to adhere also to the edge 6 or outer surface 7, or both, of the flanges.

The diaphragm 4 may be secured to the flange by any means which will provide a substantially airtight seal between the diaphragm and the shell. One practical and convenient means is a 20 suitable glue or liquid cement.

The diaphragm 4 may be put in place with a high degree of tautness, as shown in the lower shell 2 in Figure 3, or relatively loosely, as shown by dotted lines at 8 in the upper shell in Figure 25 3, depending upon the degree of tension desired.

One of the advantages of this invention is that in addition to the cushioning effect provided by the resilient diaphragms, air pressure may also be used to dampen the movements of the object being carried in the container. As before stated, 30 the diaphragms may be mounted so as to provide a substantially airtight seal between each diaphragm and its respective shell. In addition to this, the cushioning is further aided by the firm joining together of the upper and lower shells

35 as shown in Figure 2. Each shell thus, in the completed assembly, becomes an airtight compartment and the air contained between each diaphragm and the inner walls of its respective container will resist any fluctuations of the diaphragms and of the object held therebetween.

In order to effect control of the amount of vibration allowed by means of varying air pressure, a valve 9 is provided in each shell. Through each valve the amount of air in the respective shells 40 may be increased or decreased. If, for example, it is desired to keep at a minimum the movement of the object being transported, the diaphragms 4 will be positioned with as much tension as possible and a high volume of air will be pumped or otherwise introduced through the valves 9 into each shell.

The shape of the container shown in the drawings is believed to be especially convenient and practical but many different shapes could be used so long as what are referred to herein as

the upper and lower portions could be made to fit together snugly and thus be made to prevent the entry of air between the two diaphragms.

So far as the juxtaposition of the two diaphragms in operative position is concerned, it may also be desired to have them spaced apart even though each may be taut. This would be the case if bulk objects or any other object which extends vertically to a degree which might cause the puncturing of diaphragms initially abutting each other were to be carried. In such cases any suitable spacing means or gasket may be placed between the circumferences of the upper and lower portions and the locking means adjusted accordingly.

The diaphragms having been properly adjusted, the object to be carried will be placed upon the diaphragm of the lower shell 2, and preferably in the center thereof. The upper shell will then be positioned as shown in Figure 2 and the diaphragms will conform themselves in shape to the general configuration of the object between them. For illustrative purposes a watch has been shown—in Figure 1 in plan and in Figure 2 in section.

Any suitable locking or clamping means may be used to secure the two shells together in such manner that the circumferences of the respective mouths thereof abut each other. One practical and convenient locking means, a flexible partial ring 10, grooved in its inner circumference, which might be formed of metal or plastic and which fits snugly over the flanges 3, is shown in Figure 2. Other means, in fact any means, which will effect a tight juncture of the two shells might be used—for example, screws or bolts. Since precise register is desired between the flanges when they are fitted together, the form shown in the drawings is believed to be most practical—that is, a form in which the circumference of the mouth of each shell does not deviate from a common plane. Undulating, notched, etc., surfaces might be used, but the problem of register would be greater in such cases than in the form shown in the drawings.

After the locking means is in operative position, the device is ready to use, providing the air pressure in the shells is as desired. If the amount of roughness, bumpiness or turbulence to be encountered is expected to be small or if the object is not easily subject to damage, it may be that the pressure of the existing atmosphere will be satisfactory and if so, one or both of the valves 9 may be left open; or one or both may be closed with no air having been added. For some circumstances a form of the invention might be used which has no valves and in which there is no opening in the shells or in which either or both of the shells may have a small air vent as shown at 11 in Figure 10. If these vents are used, the air pressure within the shells will remain equal to the pressure in the surrounding free atmosphere. This use of the device would be especially desirable if great changes in the outer atmosphere, relative to pressure within the container, were considered harmful. If roughness or turbulence is anticipated, a form containing no vents but possessing valves will be used and additional air may be introduced into either or both of the shells through the proper valve or valves.

The shells may be formed of any substance which is sufficiently strong to withstand the shocks to be encountered and which will not permit air to transpire through it. Either one or both of the shells may be made of light, strong

metal. One convenient form is that in which the lower shell 2 is formed of metal and the upper shell 1 formed of a transparent plastic, such as Plexiglas. This form has the advantage of allowing the shape and position of the object being carried to be seen by those who handle or are otherwise responsible for the container and its contents. For even if neither diaphragm were transparent, either diaphragm, if visible, would be generally shaped or molded to the form of the object carried by its contact with that object.

In the modified form of Figures 4 and 5, instead of the double shell shown in the earlier figures, a single main shell member 12 is used. This shell is provided with an internal annular flange 13 against which a diaphragm 14 is positioned and upon which the diaphragm is held seated by a ring 15 which, as shown, is threaded to engage corresponding threading 16 on the interior of the shell 12. The shell 12 may be closed by a flat, or generally flat, cover member 17, which is held in place by screws 18, or otherwise. 19 is a gasket or sealing means between the cover 17 and the portion of the shell 12 which it contacts. The devices of the sort shown in Figures 4 and 5 may include two diaphragms, but, as shown, only a single diaphragm 14 is used. A variety of articles, indicated in dotted lines as at 20, may be placed upon the diaphragm 14 when the latter is in a more or less horizontal position, and the articles are covered by a layer of flexible material, natural or synthetic, such as latex or some plastic. This is the material indicated as at 21 in Figures 4 and 5. Although the material is shown in strictly circular pattern in Figure 5, it is to be understood that it might be of any pattern or plan and may be applied merely by spraying the latex or other material over the article so that it holds the article to the diaphragm 14. It may form a sealing contact to seal the article, or it may merely act as a holding means to hold the article to the diaphragm.

The shell 12 is provided with a check valve 22 and the cover 17 is provided with a check valve 23. One or both of these may be omitted. When present, they are useful to permit fluid under pressure to be forced into the shell on either side of the diaphragm.

The modified form of Figure 6 is substantially the same as that of Figure 2, except that the diaphragms differ. As shown in Figure 6, two diaphragms 24 are in place, and each diaphragm is provided with a thickened peripheral portion 25. When the diaphragms are put in place about the shell or housing members 1 and 2 they are merely folded or placed over the peripheral flange 3 and are sprung into place, as shown in Figure 6. Their elasticity holds them in that position, and when the device is then fastened together by the member 10, the parts assume the position and arrangement shown in Figure 6.

In Figure 8 the diaphragm is generally like that shown in Figure 7. However, it comprises a web or diaphragm portion 26 thickened at or near its center, as at 27, and provided with a thickened peripheral portion 28. The thickening, as shown in Figure 8, is progressive, increasing from a point away from the center uniformly toward the center. The diaphragm may take different form, or the thickening may be in any proportion or sequence. It is frequently useful to have a diaphragm without uniformity in thickness from edge to edge.

In the modified form of Figure 9, the structure is substantially that of Figures 1 and 2 except that instead of fastening means 10 the circumferential lips 3 are held together by screws 29. Obviously, bolts or rivets, or other fasteners, would be the general equivalents of the screws 29. Certain conditions make this positive fastening desirable. Where substantial pressures are to be developed and maintained within one portion or another of the housing this type of positive fastening is preferable.

In the several forms of the invention illustrated a relatively rigid housing or shell is provided, and a relatively flexible diaphragm is suspended under tension within the area enclosed by the housing. Thus, the diaphragm and whatever is supported by it are protected from contact with objects outside of the shell. The diaphragm is protected from breaking and the objects carried by the diaphragm are cushioned and protected from shock by the elasticity and flexibility of the diaphragm. If the diaphragm is arranged in a housing or shell which has no valves, such as the valves 9 or 23, pressure will be developed within the shell when the shell parts are joined together, and an article is supported by the diaphragm. Thus, if no compression is added to the space enclosed by the shells, the only compressive effect present is that due to the fact that the object which is supported upon a diaphragm or between diaphragms displaces its own volume of air and, hence, creates some compression. For some purposes this is sufficient. For some purposes the vents 11 will be provided in one or more of the shell housing members. The vents, of course, prevent the creation of any compression, since they permit equalization of pressure between the space within the shell and the space outside of the shell. Ordinarily, the vents will not be present if the valves 9 are used. The valves 9 find their primary use as inlets for pressure fluid after the two shell parts have been joined together, and since they open freely inwardly in response to pressure and are seated in response to pressure within, they permit pressure to be forced into the space within the shell and prevent its escape. Therefore, the vents 11 would not normally be present in a shell which is equipped with the valves 9 or their equivalent.

Sometimes it is desirable to equip one shell; for example, the shell 1, with a valve 9 and to have no vent in it and to equip the shell 2 with a vent and to have no valve in it. In this arrangement pressure will be introduced through the valve 9 inside the shell portion 1, and the air within the shell portion 2 will be somewhat displaced through the vent 11 and the diaphragm will be distorted or bowed outwardly in the direction of the shell portion 2. This distortion or stretching will increase the tension of the diaphragm and will thus tend to reduce the possible amplitude of vibration of the diaphragm under the effect of shock on the housing or shell portion 1 or 2.

If only a single diaphragm is used it will be impervious, or substantially impervious, to air. If two diaphragms are used, as shown in Figures 2, 6 and 9, at least one will be impervious to the air and the other may not be. Frequently, of course, both will be impervious and substantially identical in size, shape and in the material of which they are made.

The invention is not limited to any particular shape of shell or housing, nor to any particular style, shape or material for the diaphragm, nor

to the means of securing the diaphragm in place. Generally, the shell will be relatively rigid, although it may have some flexibility, and the diaphragm, when the parts are assembled in load-carrying position, will be taut and preferably will be subjected to pressure during use. The pressure may be utilized on both sides of the diaphragm or it may be unequal. It is unequal the diaphragm will tend to be deformed. If it is equal the diaphragm will tend to be retained in flat position. The means for securing the diaphragms together; for example, the part 10 or the screws 29, or any other suitable fastening means, will be selected in accordance with particular conditions of use. If high compression is to be used, obviously the spring fastening means 10 of Figures 1, 2, 3, and 6 would not be suitable, and a more positive fastening means, such as that shown in Figures 4 and 9, is necessary.

Although I have shown an operative form of my invention, it will be recognized that many changes in the form, shape and arrangement of parts can be made without departing from the spirit of the invention, and my showing is, therefore, to be taken as, in a sense, diagrammatic.

I claim:

1. In a container, concave mating portions, each of the said portions being relatively rigid and being formed of material impervious to the passage of air therethrough; a resilient diaphragm positioned across the mouth of each of said portions under tension, said diaphragms being impervious to the passage of air therethrough, each of said diaphragms being secured to the circumference of the mouth of its respective portion so as to form a substantially airtight seal therein, and locking means joining said portions together in register at the circumferences of the respective mouths thereof, the tension of the said diaphragms being such as to permit the positioning therebetween of an object to be carried in the container.
2. In a container, concave mating portions, each of the said portions being relatively rigid and being formed of material impervious to the passage of air therethrough; a resilient diaphragm positioned across the mouth of each of said portions under tension; a flange extending outwardly from the circumference of the mouth of each of said portions, each of said diaphragms being secured to the circumference of its respective portion; and locking means joining said flanges in register, said locking means comprising a flexible partial ring, grooved in its inner circumference and positioned snugly over the said flanges; the tension of the said diaphragms being such as to permit the positioning therebetween of an object to be carried in the container.

3. In a container, concave mating portions, each of the said portions being relatively rigid and being formed of material impervious to the passage of air therethrough; a resilient diaphragm positioned across the mouth of each of said portions under tension, said diaphragms being impervious to the passage of air therethrough, each of said diaphragms being secured to the circumference of the mouth of its respective portion so as to form a substantially airtight seal therein; a valve positioned in the wall of one of said portions, adapted to permit the control of the air pressure therein; and locking means joining said upper portion and said lower portion together in register at the circumferences of the respective mouths thereof, the tension of the said diaphragms being such as to permit the positioning

therebetween of an object to be carried in the container.

4. In a container, concave mating portions, each of the said portions being relatively rigid and being formed of material impervious to the passage of air therethrough; a resilient diaphragm positioned across the mouth of each of said portions under tension, said diaphragms being impervious to the passage of air therethrough, each of said diaphragms being secured to the circumference of the mouth of its respective portion so as to form a substantially airtight seal therein; a valve positioned in the wall of each of said portions, adapted to permit the control of the air pressure therein; and locking means joining said portions in register, the tension of said diaphragms being such as to permit the positioning therebetween of an object to be carried in the container.

5. In a container, concave mating portions, each of the said portions being relatively rigid and being formed of material impervious to the passage of air therethrough; a resilient diaphragm positioned across the mouth of each of said portions under tension, said diaphragms being impervious to the passage of air therethrough, each of said diaphragms being secured to the circumference of the mouth of its respective portion so as to form a substantially airtight seal therein;

10

an air vent positioned in the wall of each of said portions, adapted to permit the control of the air pressure therein; and locking means joining said upper portion and said lower portion together in register at the circumferences of the respective mouths thereof, the tension of the said diaphragms being such as to permit the positioning therebetween of an object to be carried in the container.
